(57) **CLAIM**

The ornamental design for a monocular, as shown and described.

DESCRIPTION

FIG. 1 is a front perspective view of a monocular showing my new design;

FIG. 2 is a top plan view of the embodiment shown in FIG. 1 illustrating a control button arrangement;

FIG. 3 is a right side elevational view thereof, the left side is a mirror image;

FIG. 4 is a bottom plan view of the embodiment shown in FIG. 1;

FIG. 5 is a front elevational view thereof, the broken line showing of the labels is for illustrative purposes only and forms no part of the claimed design; and,

FIG. 6 is a rear plan view of the embodiment shown in FIG. 1, illustrating the ocular placement.
